UNITED STATES PATENT OFFICE.

FRANCIS A. J. FITZ GERALD, OF NIAGARA FALLS, NEW YORK, ASSIGNOR TO REPUBLIC CARBON COMPANY, INC., OF NIAGARA FALLS, NEW YORK, A CORPORATION OF DELAWARE.

ELECTRIC FURNACE.

Application filed December 9, 1920. Serial No. 429,402.

To all whom it may concern:

Be it known that I, FRANCIS A. J. FITZ GERALD, a citizen of the United States of America, and a resident of the city of Niagara Falls, county of Niagara, and State of New York, have invented certain new and useful Improvements in Electric Furnaces, of which the following is a full, clear, and exact description.

It is well known to those skilled in the art, that in the manufacture of various materials in which carbon is an element, it is desirable and even necessary to subject the carbonaceous substance, from which the carbon is derived, to certain treatments among which calcination, at a high temperature, is one of the most important. This process is carried on in various ways, among which the use of the electric furnace is one. My invention relates particularly to an electric furnace of this type.

The principal object of my invention has been to provide a furnace in which carbonaceous materials may be calcined with great uniformity, as the rate of feed of the material to the furnace may be made directly, in proportion to the amount of current used in the furnace.

It is well known that, in furnaces of this type, where the bottom of the furnace forms one electrode, the current must pass through the entire charge of the furnace. In producing my invention, I have sought to overcome this and have provided a furnace in which the generation of heat is always confined to that part of the charge which is in the process of calcination. As the carbonaceous material already calcined is a good conductor of electricity, little heat is generated by the passage of the current through it, thus it forms an electric conductor for the current used, so that the current doing work is confined to the material being calcined. Therefore, throughout the whole operation, the electric power is always confined to substantially the same quantity of material, thus producing a uniformly calcined product.

Furthermore, the construction of my furnace is such that it may be advantageously used in plants, operating under peak loads, as great quantities of electricity may be used

in the furnace when such quantities are available, and a product produced which is uniformly calcined irrespective of the amount of current used.

The above objects and advantages have been accomplished by the device shown in the accompanying drawings, of which:

Fig. 1 shows a side elevation of my device, partly in section and somewhat diagrammatical.

Fig. 2 is a plan view of the same.

The furnace comprises a steel shell 5, having a bottom 6, and being reinforced preferably at its upper edge by the angle irons 7, 8 and 9 are trunnions, which are secured to the sides of the shell at diametrical opposite points. By these trunnions the furnace may be raised and its contents dumped.

10 is a tray, arranged beneath the furnace and provided with a plurality of bricks 11, or other suitable separators, whereby a space 12 is provided beneath the bottom 6 of the furnace shell. Surrounding the shell 5, at its upper end, is a cooling pipe 13, which is provided with a plurality of perforations 14, whereby cooling fluid, conducted to the pipe 13, will be projected against the outer surface of the furnace shell. The cooling fluid which passes over the surface of the furnace shell 5 is collected in the tray 10 and is drained therefrom by means of the drain pipe 15 provided therein. The upper end of the drain pipe 15 is slightly above the bottom 6 of the furnace shell, so that the bottom of the shell will always be immersed in the cooling fluid.

The furnace shell 5 is provided with a refractory lining 16 and the bottom thereof is provided with a carbon lining 17. The refractory lining 16 is of such a nature that it not only has a high resistance to heat, but also is a non-conductor of electricity. Most refractories that are non-conductors of electricity, have this characteristic only when they are kept cool. Furthermore, almost all refractories react with carbon at high temperatures. It is necessary, therefore, to keep the refractory lining 16 at such a temperature that it will remain a non-conductor of electricity and that the carbonaceous material contained in the furnace will not react

with it. This is accomplished preferably by means of the cooling pipe 13 and shell 5. In my furnace two electrodes 18 and 19 are employed, the current passing from one electrode to the bottom 17 or the calcined carbonaceous material in the furnace to the other electrode. 20 is the source of electric current used in the furnace, and, for clearness of illustration, is shown in a diagrammatic manner. 21 and 22 are the conductors which connect the source of electrical energy 20 with the electrodes 18 and 19, respectively. Some suitable means are provided for raising and lowering the electrodes 18 and 19, which, for clearness of illustration, have been omitted from the drawings.

Assuming that my furnace is to be used to calcine anthracite coal to a certain specific degree, the coal is first crushed to the desired size and a little is fed into the furnace. The electrodes are then lowered until an electrical contact is made with the carbon lining 17 of the bottom of the furnace. The current which passes between the electrodes and the bottom will heat the coal and calcine it. During this time additional coal is fed into the furnace while the electrodes are adjusted vertically so as to keep the current constant and maintain the same voltage difference between the electrodes and the charge. This adjustment may be accomplished either manually or automatically, the means for carrying out these methods being well known to those skilled in the art and, therefore, not herein illustrated or described. This process is continued until the furnace is filled, after which the current is shut off and the electrodes are removed from the furnace. When the charge has sufficiently cooled, the furnace is picked up by the trunnions and the contents dumped into a suitable receptacle.

In the drawings, I have shown my invention as applied to single phase current, where only two electrodes are necessary. It is obvious, however, that where, for instance, three-phase current is employed, the furnace would be provided with three electrodes or some multiple thereof. These and other modifications, which will be apparent to those skilled in the art, may be made without departing from the spirit of my invention or the scope of the appended claims; and I do not, therefore, wish to be limited to the exact embodiment herein shown and described, the form described being merely a preferred embodiment thereof.

Having thus described my invention, what I claim is:

1. An electric furnace for calcining carbonaceous materials comprising an outer shell; a carbon bottom for the shell, a refractory lining for the shell, vertically and separably movable electrodes for the furnace and means for cooling the lining.

2. An electric furnace for calcining carbonaceous materials comprising an outer shell, a carbon bottom for the shell, a refractory lining for the shell, vertically and separately movable electrodes of opposite polarity for the furnace, and means for cooling the lining.

3. An electric furnace for calcining carbonaceous materials comprising an outer shell, a carbon bottom for said shell, a refractory lining for said shell, vertically movable electrodes for the furnace, means for cooling the lining of the furnace, and means for lifting the furnace shell and emptying the charge.

4. An electric furnace for calcining carbonaceous materials comprising an outer shell, a carbon bottom for said shell, a refractory lining for said shell, vertically and separably movable electrodes for the furnace, and a perforated pipe arranged around the exterior of the shell at its upper edge, whereby the exterior of the shell is cooled by the flow of a cooling fluid through the perforations of said pipe.

5. An electric furnace for calcining carbonaceous materials comprising an outer shell, a carbon bottom for said shell, a refractory lining for said shell, vertically movable electrodes for the furnace, a tray arranged beneath the furnace shell, separators between the tray and the bottom of the shell, and means for cooling the lining.

6. An electric furnace for calcining carbonaceous materials comprising an outer shell, a carbon bottom for said shell, a refractory lining for said shell, vertically movable electrodes for the furnace, a tray arranged beneath the furnace shell, separators between the tray and the bottom of the shell, a drain pipe for the tray, arranged so as to maintain a definite height of cooling fluid in the tray, and a perforated pipe arranged around the furnace shell, whereby cooling fluid may be flowed over the exterior of the shell and the bottom thereof immersed in the cooling fluid.

In testimony whereof, I have hereunto signed my name.

FRANCIS A. J. FITZ GERALD.
